US00D762578S

(12) **United States Design Patent**
Chen et al.

(10) **Patent No.:** US D762,578 S
(45) **Date of Patent:** ** Aug. 2, 2016

(54) **TERMINAL OF ELECTRICAL BATTERY CONNECTOR**

(71) Applicant: **ADVANCED-CONNECTEK INC.**,
New Taipei (TW)

(72) Inventors: **Ching-Tien Chen**, New Taipei (TW);
Shu-Lin Duan, New Taipei (TW); **Wei Wan**, New Taipei (TW); **Ping-Chung Chu**, New Taipei (TW); **Xiao-Juan Qi**, New Taipei (TW)

(73) Assignee: **ADVANCED-CONNECTEK INC.**,
New Taipei (TW)

(**) Term: **15 Years**

(21) Appl. No.: **29/535,028**

(22) Filed: **Aug. 3, 2015**

(30) **Foreign Application Priority Data**

Feb. 3, 2015 (TW) 104300545

(57) **CLAIM**

The ornamental design for a terminal of electrical battery connector, as shown and described.

DESCRIPTION

FIG. 1 is a top perspective view of a terminal of electrical battery connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.
